UNITED STATES PATENT OFFICE

DOUGLAS C. JEFFREY, OF AKRON, AND HOMER J. MARSHAM, OF OAKFIELD, NEW YORK,
ASSIGNORS TO UNIVERSAL GYPSUM & LIME CO., OF CHICAGO, ILLINOIS, A COR-
PORATION OF DELAWARE

LATH BUNDLING APPARATUS

Application filed April 8, 1929. Serial No. 353,570.

Our invention relates to machines for bundling pieces of wall board of a size adapted for use as lath or as a substitute for lath so as to make such pieces capable of being handled readily in shipment and on the job at the place of use. It is one of the objects of our invention to provide a novel arrangement of parts in a machine of this type by reason of which the bundling machine as a whole is capable of being moved easily and quickly into and out of position adjacent to the discharge of the kiln through which the board is directed for drying as it comes from the board forming machine, or is capable of being moved to convenient position with respect to the place of storage of board or lath which is to be bundled.

It is one of the objects of our invention to provide a machine of this type organized and arranged with particular reference to the construction of the parts at the discharge end of the kiln whereby the pieces of board can be handled to the best advantage for feeding forwardly into the bundling machine.

It is one of the objects of our invention to provide improved feeding means for machines of this type whereby the required number of pieces of board may be fed forwardly automatically in timed relation from a previously piled supply without the necessity for constant personal attention, thereby permitting the attendants to give attention as may be necessary to other details of the bundling operation.

It is one of the objects of our invention to provide an improved arrangement of means for holding the pieces of board in position and for moving them forward for the application of gummed tape binders to the edges of the bundles in such manner as to hold the bundles together in unit form. It is another object of our invention to provide improved means for holding the edge portions of the gummed tapes in contact with the faces of the outside boards of the bundle until the tapes are dried sufficiently for maintaining the bundle intact.

It is another object of our invention to improve devices of this type in sundry details hereinafter pointed out. The preferred

means by which we have accomplished our several objects are illustrated in the accompanying drawings and are hereinafter specifically described. That which we believe to be new and desire to cover by Letters 55 Patent is set forth in the claims.

In the drawings,—

Fig. 1 is a top plan view of our improved machine;

Fig. 2 is a side view of the machine as shown in Fig. 1, with a plurality of superposed piles 60 of pieces of board in the course of being bundled;

Fig. 3 is a perspective view of the form of bundle prepared by the machine of Figs. 1 65 and 2;

Fig. 4 is a side view of one end portion of the machine, being shown upon a considerably enlarged scale;

Fig. 5 is an enlarged detail showing the 70 construction of the auxiliary frame upon which folders are mounted for applying the adhesive tape to the piles of board;

Fig. 6 is an enlarged detail showing a fragmentary portion of the construction in connection with the rolls of tape;

Fig. 7 is an enlarged detail, being substantially a section at line 7—7 of Fig. 6.

Referring now to Figs. 1 to 7, in which corresponding parts are indicated by the same reference characters, 10 and 11 indicate heavy angle irons forming the side bars of the rear end portion of the frame-work of our improved machine, said bars being connected at their forward ends to angle irons 12 and 13, 80 respectively. The angle irons 10 to 13 are connected together by suitable cross bars and are connected to a bottom frame 14 by means of a plurality of standards 15, diagonal brace bars 16 being provided between one end of the bottom frame portion 14 and an intermediate portion of the top frame portion. Carrying wheels 17 of any suitable type are journaled upon a transverse axis at about the middle point of the frame, and one or more caster 90 wheels 18 are provided at the forward end of the frame, the arrangement being such that the machine as a whole is capable of ready transportation on said carrying wheels. At the rear end, one or more pivotally mounted 95

supporting bars 19 are provided serving to assist in holding the frame-work rigidly in its adjusted position.

Upon the forward end of the machine, we have provided an endless conveyor belt 20 of any approved type extending about a tail pulley 21 at its rear end and a head pulley 22 at its forward end. A plurality of supporting rollers 23 are provided across the frame-work underneath the top ply of the conveyor belt 20, such supporting rollers 23 being of any approved type. A supporting roller 24 is also provided underneath the bottom ply of the belt, as is best shown in Fig. 2. Guide rollers 25 are provided at opposite sides of the machine near the rear end of the belt for controlling the position of the belt transversely of the machine.

The conveyor belt 20 is driven, in the construction shown, by means of a gear 26 on the shaft of the head pulley 22, such gear 26 meshing with a pinion 27 carried by an idler shaft which in turn is provided with a sprocket gear 28 connected by means of a sprocket chain 29 with the driving gear 30 of an electric motor 31 carried by the frame-work.

In rear of the conveyor belt 20 we have provided a plurality of rollers 32 extending across the frame-work in transverse position. Each of the shafts 33 upon which the rollers 32 are mounted is provided at one side of the machine with a sprocket gear 34, such gears being connected with a sprocket gear 35 carried by the shaft of the tail pulley 21, such connection being effected by means of a sprocket chain 36 at one side of the machine, a sprocket chain 37 at the opposite side of the machine, and intervening gearing comprising sprocket wheels 38 and an idler shaft 39. The arrangement is such that the rollers 32 are driven at a very slightly greater surface speed than that at which the conveyor belt 20 is driven.

In the construction shown, we have provided an end stop at a point located approximately four feet from the rear end of the machine. As is best shown in Fig. 4, this end stop comprises a cross board 40 which is slidable vertical under control of screws 41 at opposite sides of the machine, the arrangement being such that by turning the screws the vertical position of the stop can be varied for bringing the lower edge of the stop into changed vertical position above the level of the driven rollers 32.

At the rear end of the machine, we have provided two supporting rollers 42 and 43 at the same level as that of the driven rollers 32, and at substantially the extreme end of the machine we have provided an idler 44 at a slightly higher level. At the near side of the machine as shown in Fig. 1, we have provided vertically extending guide rollers 45 and 46.

The arrangement is such that when a pile 47 (see Fig. 4) of superposed pieces of board

are in position upon the driven rollers 32 with the rear end of the pile extending rearwardly beyond the end stop 40, a second pile 48 of superposed pieces of board can be placed in position with its front end resting upon the rear end portion of the pile 47 adjacent to the end stop 40, and with its rear end portion resting upon the transverse roller 44, the roller 44 being preferably at such a level as to support the pile 48 in slightly raised angular position with respect to the level of the top faces of the rollers 32, 43 and 42. In placing in position the boards comprising the pile 48, one or more boards are preferably handled at a time, such boards being adjusted to have their forward ends in contact with the end stop 40 and their side edges against the guide rollers 45 and 46, the guide rollers 45 and 46 being placed in such position transversely of the machine for assuring that the pile will be in the desired centered position on the machine. Additional piles 49 and 50 can then be placed in position above the pile 48, each successive pile preferably being placed slightly farther toward the rear than the pile upon which it rests.

Top pressure rollers 51 and 52 are provided for engaging the top face of the pile of boards resting upon the driven rollers 32 such rollers 51 and 52 being journaled in transverse position between side bars 53, such side bars 53 comprising with the rollers an auxiliary frame. As is clearly shown in Fig. 4 the rear end of the auxiliary frame extends above the end stop plate 40 whereby such end stop plate is adapted to limit the downward movement of the frame and of the rollers 51 and 52. The forward end of the frame comprising the side bars 53 is provided with downwardly extending arms 54 rigidly connected with said frame in any suitable manner at opposite sides of the machine, such arms 54 being pivotally and slidably connected with the main frame bars 10 and 11 by means of pivot pins 54a working in slots 54b. By this construction, the auxiliary frame is movable vertically with respect to the driven rollers 32 whereby the weight of the top pressure rollers 51 and 52 is brought to bear upon the top faces of the successive piles of superposed pieces of board in position upon the driven rollers.

The means for supporting the adhesive tape binders to be applied to the edge portions of the piles of board comprises, in the construction shown, a channel bar 55 extending across the main frame-work. Upon opposite ends of the channel 55, we provide rearwardly extending arms 56 provided at their rear end portions with vertically extending spindles 57 upon which rolls of adhesive tape 58 are adapted to be mounted, as is best shown in Figs. 6 and 7. Arms 59

are pivotally mounted in position carrying at their rear ends a pressure bar 60 which is adapted to bear against the outer face of the roll of tape, such pressure bars being held 5 yeldingly in contact with the roll 68 by means of coiled springs 61. Slightly in advance of the rolls 58, we have provided felt covered moistening rollers 62 suitably supported in position, such rollers 62 having their lower 10 ends mounted in the channel bar 55. The upper ends of the rollers 62 are provided with reservoirs for receiving water from any suitable source, such as through a hose 63, the water being adapted to overflow constantly 15 for moistening the felt coverings of the rollers. The excess water is taken care of by a drain 55a of any suitable type.

At each side of the machine adjacent to the tape holding and moistening means just described, we have provided an auxiliary frame 64, the form of the frame-work in the construction shown being illustrated in Fig. 5. Each of the auxiliary frames 64 is pivotally mounted by means of vertically extending 25 pins 65 upon the main frame bars so as to be capable of swinging thereabout. At the rear end of each of the auxiliary frames 64, there is mounted a guide roller 66. Extending forwardly from the frame 64 at each side of the 30 machine, there is a sheet metal folder 67, such folder being yeldingly supported upon the frame-work by means of a flexible strip 68 and by means of pins 69 carried by the folder and extending through openings in an arm 35 70 extending forwardly from the frames. A coiled spring 71 is mounted upon one of the pins 69 at each side of the machine. The arrangement is such that the folders 67 are adapted to yield outwardly with respect to 40 the auxiliary frames 64.

The folders 67 are formed of sheet metal bent into shape, the side flanges of each of the folders being supported by means of a bracket 72 extending thereabout with a block of rubber 73 or other yielding material interposed between the bracket and one of the flanges for permitting outward yielding of the sides of the folder as may be necessary.

In advance of the folders 67 by which the 50 adhesive tapes are applied as hereinafter described, we have provided an additional auxiliary frame 75 provided with transversely extending top pressure rollers 76 and 77. Extending forwardly from the auxiliary frame 55 75, there are flexible strips 78 which serve as ironing devices as hereinafter described, such strips being preferably provided with weight members 78a at intervals therealong for rendering the strips effective as ironing devices. 60 As is clearly shown in Figs. 1 and 2, a cross bar 75a of the frame 75 by engagement with upright bars of the frame 15 prevents forward movement of said frame 75 while at the same time permitting vertical movement.

65 With the machine in position at the outlet

of a kiln within which plaster board lath are being dried as they come from a board forming machine, or with the machine in some desired position otherwise with respect to the pieces of board to be bundled, the electric motor 31 is started into operation for driving the conveyor belt 20 so as to carry its top ply forwardly or toward the right in Figs. 1 and 2, and for driving the rollers 32 in clockwise direction in Fig. 4. A pile of board is then placed in position and is fed forwardly underneath the end stop 40 through the action of the driven rollers 32. As the front end of the pile comes underneath the pressure rollers 51 and 52, such rollers apply downward pressure upon the pile. When the front end of the pile of superposed pieces of board is brought between the flanges of the folder 67, the tapes from the rolls 58 are applied to the edges of the pile through the action of the folder 67 such tapes having been threaded about the moistening rollers 62 and the guide rollers 66, as is clearly shown in Fig. 6. For the first pile of board passing through the machine, the forward end of the tape is pressed manually into contact with the pile so as to carry the tape through the folder 67 as the pile moves forward.

When the rear end of the pile of superposed pieces passes forwardly beyond the end stop 40, the forward end of the next higher pile of board which has in the meantime been piled manually in position, drops into engagement with one of the driven rollers 32 so as to cause such pile of pieces of board to pass forward immediately following the preceding pile, the frictional contact of the several boards with each other being sufficient to insure continued alignment of the pieces in piled relation. As soon as such pile has moved forward a very short distance, its rear end in turn drops out of contact with the roller 44, whereupon the operation continues. When the next succeeding pile of superposed pieces of board is brought into engagement with the end stop 40, the forward movement of the top piles at the rear end of the machine is stopped temporarily, the frictional engagement between the pile supported directly by the roller 44 and the pile beneath being sufficient for causing the piles to move forward to the end stop but being insufficient to cause trouble after such stoppage.

Inasmuch as the driven rollers 32 normally carry a pile of board forward at a slightly more rapid rate than that at which the pile is carried forward by the conveyor belt 20, it will be understood that the piles of board will follow each other without intervening spaces at the point where the tapes are applied to the piles of board. By this means, any slight delay which is caused in connection with the automatic feeding of the piles of board is compensated for. With one pile following immediately after the preceding pile, the

115

120

125

130

tapes from the rolls 58 will be fed forward continuously without the necessity for any sort of manual control.

By the provision of the auxiliary frames

5 64, the guide rollers 66 are free to move outwardly whenever there may possibly be a slight variation in the width of the pieces of board. Such outward movement of the rollers 66 would have a tendency to move the 10 folders 67 inwardly, but the outward yielding of the folders 67 with respect to the frames 64 is permitted as may be necessary by reason of the yielding mounting of the 15 folders with respect to such auxiliary frames.

15 In the use of our improved apparatus, in which the rollers 32 are driven at a slightly higher surface speed than that at which the conveyor belt 20 is adapted to run, when a 20 pile of boards is brought by the rollers 32 into engagement with the rear end of the next preceding pile the rollers 32 thereafter slip to the slight extent necessary with respect to the pile of boards resting thereon, the action of the rollers 32 being comparative- 25 ly less positive than that of the conveyor belt 20.

The conveyor 20 is normally driven at a speed slightly greater than that necessary for taking care of the output of the 30 board producing machine and the kiln, so that time is provided for stopping the machine at intervals as may be necessary or desired for substituting a fresh roll of gummed paper or for any other suitable purpose.

35 As the tapes are applied to the opposite edges of the piles of boards, such piles are carried forward underneath the top pressure rollers 76 and 77 which smooth down and apply pressure to the edge portions of the 40 tapes for pressing them firmly into contact with the outside faces of the boards of the pile, and the flexible strips 78 serve to hold such edge portions of the tape in continued contact with the board until the adhesive has 45 set sufficiently for maintaining the pile in unit bundle form.

As the bundles come to the forward end of the machine, an attendant cuts the adhesive tapes between successive bundles, and the 50 bundles are taken from the machine.

By the use of our improved machine, a bundle 80 such as is shown in Fig. 3 is provided, comprising a plurality of pieces of board held together by adhesive tape binders 55 81 at its opposite edge portions, such adhesive tape binders being in the construction illustrated in Fig. 3 continuous from end to end of the bundle. The bundle 80 is preferably composed of six pieces of board sixteen inches 60 wide and forty-eight inches long.

While we prefer to employ the form of machine as shown in our drawings and as above described, it is to be understood that we do not wish to limit our invention to the form 65 shown except so far as the claims may be so

limited by the prior art, it being understood that changes might well be made without departing from our invention.

We claim:

1. A machine of the type described, comprising in combination conveyor means for carrying along in superposed piled relation a plurality of pieces of board, and means adapted as the pieces pass forward to apply adhesive tape binders about edge portions of the pile for holding the pieces of board together in unit bundle form. 70

2. A machine of the type described, comprising in combination conveyor means for carrying along in superposed piled relation a plurality of pieces of board, pressure means free to move either upwardly or downwardly and arranged to have its principal support from successive piles of boards for pressing the boards together as they move forward, and means adapted as the compressed pile moves forward to apply adhesive tape binders to edge portions of the pile for holding the pieces of board together in unit bundle form. 80

3. A machine of the type described, comprising in combination a conveyor for carrying forward in superposed piled relation a plurality of pieces of board, means in rear of said conveyor serving normally to feed said pile boards at a slightly higher speed of movement to said conveyor, and means adapted as the pieces pass forward to apply adhesive tape binders about edge portions of the pile for holding the pieces of board together in unit bundle form. 90

4. A machine of the type described, comprising in combination a conveyor for carrying forward in superposed piled relation a plurality of pieces of board, means in rear of said conveyor of slightly less positive action serving normally to feed said piles of boards at a slightly higher speed of movement to said conveyor, and means adapted as the pieces pass forward to apply adhesive tape binders about edge portions of the pile for holding the pieces of board together in unit bundle form. 100

5. A machine of the type described, comprising in combination an endless belt conveyor for carrying forward in superposed piled relation a plurality of pieces of board, driven rollers in rear of said belt conveyor for feeding said piles of boards to said conveyor, and means adapted as the pieces pass forward to apply adhesive tape binders about the edge portions of the pile for holding the pieces of board together in unit bundle form. 115

6. In a machine of the class described, the combination of conveyor means comprising an endless belt for carrying forward a plurality of pieces of board in superposed piled relation, pressure means free to move either upwardly or downwardly and arranged to have its principal support from successive piles of board for pressing the boards to- 125

gether as they move forward, and means adapted as the compressed piles move forward to apply adhesive tape binders about opposite edge portions of successive piles for holding the pieces of board together in compressed unit bundle form.

7. A machine of the type described, comprising in combination an endless belt conveyor for carrying forward in superposed piled relation a plurality of pieces of board, rollers in rear of said belt conveyor driven at such speed as normally to feed the piled boards forward to said conveyor at a slightly higher speed than that of the conveyor, and means adapted as the pieces pass forward to apply adhesive tape binders about edge portions of the pile for holding the pieces of board together in unit bundle form.

8. A machine of the type described, comprising in combination conveyor means for carrying along in superposed piled relation a plurality of pieces of board, weighted pressure means floatingly mounted so as to be supported principally by said piles of boards for applying yielding downward pressure on said piles as they pass along, and means adapted as the pieces pass forward to apply adhesive tape binders about edge portions of the pile for holding the pieces of board together in unit bundle form.

9. A machine of the type described, comprising in combination conveyor means for carrying forward a plurality of pieces of board in superposed piled relation, means adapted as the boards pass forward to apply adhesive tape binders about opposite edges of the pile, pressure means for pressing the boards firmly together as they approach said binder applying means, and other pressure means in spaced relation to said first named pressure means on the opposite side of said binder applying means for continuing the pressure on said boards as they pass forwardly.

45 10. A machine of the type described, comprising in combination conveyor means for carrying forward a plurality of pieces of board in superposed piled relation, means adapted as the boards pass forward to apply adhesive tape binders about opposite edges of the pile, floatingly mounted pressure means in rear of said binder applying means for applying initial pressure to the boards, and other floatingly mounted pressure means serving to apply downward pressure on said boards in advance of the binder applying means before said boards pass out of the influence of said first named pressure means.

60 11. A machine of the type described, comprising in combination conveyor means for carrying forward a plurality of pieces of board in superposed piled relation, two auxiliary frames floatingly mounted above said pile in spaced relation therealong and each having a plurality of pressure rollers rev-

65 olably mounted in transverse position thereon for pressing the boards firmly together as they pass forward along said conveyor, and means located between said spaced auxiliary frames for applying adhesive tape binders about both edges of the pile of boards while the pile is maintained in compressed relation as it is carried forward.

70 12. A machine of the type described, comprising in combination conveyor means for carrying forward a plurality of pieces of board in superposed piled relation, means adapted as the boards pass forward to apply adhesive tape binders about opposite edges of the pile, pressure means for applying downward pressure on said pile of boards as they pass forward to said binder applying means, and means for supporting other pieces of board in superposed piled relation to each other above the pile of boards on the conveyor so as to apply downward pressure on said pile as it moves forward to said first named pressure applying means.

75 13. A machine of the type described, comprising in combination conveyor means for carrying forward a plurality of pieces of board in superposed piled relation, means adapted as the boards pass forward to apply adhesive tape binders about opposite edges of the pile, pressure means for applying downward pressure on said pile of boards as they pass forward to said binder applying means, and means in rear of said pressure applying means for supporting the rear end of a second pile of pieces of board in such position above the pile on the conveyor that the forward end of said second pile is supported by said first named pile for applying downward pressure thereto as said first named pile moves forward to said first named pressure means.

80 14. A machine of the type described, comprising in combination conveyor means for carrying forward a plurality of pieces of board in superposed piled relation, means adapted as the boards pass forward to apply adhesive tape binders about opposite edges of the pile, pressure means for applying downward pressure on said pile of boards as they pass forward to said binder applying means, and a roller for supporting the rear end of a second pile of superposed boards at a slightly higher level than the top face of said first named pile on the conveyor whereby downward pressure is applied to said first named pile by said second pile as said first named pile moves forward to said first named pressure applying means.

85 15. A machine of the type described, comprising in combination a frame, conveyor means movable longitudinally of the frame for carrying forward in superposed relation a plurality of pieces of board, auxiliary frames pivotally mounted on vertical axes on said first named frames on opposite sides

of the conveyor means, rollers journaled on vertical axes on the end portions of said auxiliary frames respectively at the level of said piles of boards, means for feeding moist adhesive tapes to said rollers, and 5 folders resiliently mounted on the forward ends of said auxiliary frames adapted as the piles move forward to apply said tapes about edge portions of the piles for holding 10 the pieces of board together in unit bundle form.

16. A machine of the type described, comprising in combination a frame, carrying wheels on said frame, conveyor means movable longitudinally of the frame for carrying forward in superposed piled relation a plurality of pieces of board, and means mounted on said frame adapted as the pieces of board pass forward to apply adhesive tape binders about edge portions of the pile for 20 holding the pieces of board together in unit bundle form.

17. A machine of the type described, comprising in combination a frame, carrying wheels journaled on an axis extending transversely of the frame at an intermediate point, a carrying wheel journaled on a horizontal axis and adjustable about a vertical axis at one end of said frame, a pivotally mounted leg at the opposite end of said frame, conveyor means movable longitudinally of the frame for carrying forward in superposed piled relation a plurality of pieces of board, and means mounted on said frame adapted 30 as the pieces of board pass forward to apply adhesive tape binders about edge portions of the pile for holding the pieces of board together in unit bundle form.

18. A machine of the type described comprising in combination a frame, conveyor means movable longitudinally of the frame for carrying forward in superposed relation a plurality of pieces of board, means for applying adhesive tape binders about edge portions of said piles of board as they move forward, and weighted flexible strips connected 45 with said frame and extending forwardly under which said binders are carried as the piles pass forward for insuring secure bonding of the binders with the faces of the outside boards of the side boards of the piles.

19. A machine of the type described, comprising in combination a frame, conveyor means movable longitudinally of the frame for carrying forward in superposed relation a plurality of pieces of board, means for applying adhesive tape binders about edge portions of said piles of board as they move forward, an auxiliary frame movable vertically above said first named frame at a point 55 slightly in rear of that at which said tapes are applied, and rollers journaled in transverse position in said auxiliary frame for pressing said binders tight against the boards 60 of the piles.

20. A machine of the type described, comprising in combination a frame, conveyor means movable longitudinally of the frame for carrying forward in superposed relation a plurality of pieces of board, means for applying adhesive tape binders about edge portions of said piles of board as they move forward, an auxiliary frame movable vertically above said first named frame at a point 70 slightly in rear of that at which said tapes are applied, rollers journaled in transverse position in said auxiliary frame for pressing said binders tight against the boards of the piles, and weighted flexible strips connected with said auxiliary frame and extending 75 forwardly therefrom under which said binders are carried as the piles move forward for insuring secure bonding of the binders with the faces of the outside boards of the bundles.
